No. 36,757.

Patented January 26, 1904.

UNITED STATES PATENT OFFICE.

SIDNEY A. KELLER, OF NEW YORK, N. Y., ASSIGNOR TO BRISTOL MANUFACTURING COMPANY, A CORPORATION OF RHODE ISLAND.

DESIGN FOR A BROOCH, BUTTON, OR BUCKLE-PLATE, OR SIMILAR ARTICLE.

SPECIFICATION forming part of Design No. 36,757, dated January 26, 1904.

Application filed December 30, 1903. Serial No. 187,233. Term of patent 3½ years.

To all whom it may concern:

Be it known that I, SIDNEY A. KELLER, a citizen of the United States, residing at New York city, in the borough of Manhattan and State of New York, have invented a certain new, original, and ornamental Design for a Brooch, Button, or Buckle-Plate, or Similar Article, of which the following is a specification, reference being had therein to the accompanying drawing.

The drawing represents a face view of a buckle-plate embodying my new design.

What I claim is—

The ornamental design for a brooch, button, or buckle-plate, or similar article, as herein shown.

SIDNEY A. KELLER.
